UNITED STATES PATENT OFFICE

JOHN P. SIEBE, OF SACRAMENTO, CALIFORNIA

PRICE-TAG HOLDER

Application filed March 14, 1929. Serial No. 347,021.

The invention relates to devices for holding price tags on articles of merchandise and has for its object the provision of a price tag holder including a frame adapted to removably support a price card or the like, and having means carried by said frame to hold the frame and the price card on the article of merchandise.

A further object of the invention is the provision of a price tag holder consisting of a plate of sheet metal having means to hold thereon a price card and having a securing means adapted to engage an article of merchandise and support said plate.

15 A further object of the invention is the provision of a price tag holder comprising a price card frame formed of a plate of sheet metal having its edges turned and spaced to provide means to support a price card, said 20 plate having cut out portions forming tongues bent back on the plate, integral therewith and engaging the wire holding means adapted to engage an article of merchandise to hold the price tag support on the article.

25 The invention will be described in detail hereinafter and will be found illustrated in the accompanying drawings, in which

Figure 1 is a perspective view of one form of price tag holder showing it applied to an 30 article of merchandise,

Figure 2 is a top plan view of the price tag holder removed from the article of merchandise,

Figure 3 is a rear view of the holder frame 35 for the price card, and

Figures 4 and 5 are transverse sectional views on planes indicated by lines 4—4 and 5—5 of Figure 2.

In the drawings similar reference characters are used to designate corresponding 40 parts throughout the several views.

In the form of the invention shown in Figures 1 to 5, inclusive, the price tag holder comprises a frame 1 formed of a sheet metal plate 2, having its bottom edge folded as shown at 3, and its end edges folded as shown at 4, to form spaced flanges to hold a price card 5 and to permit removal and replacement thereof as desired. The body of the 45 plate 2 has tongues 6, 7 and 8 formed there-

from by cutting the plate, and the tongues bent back on the rear side of the plate 2 to engage a length of wire 9 that is adapted to enclose an article of merchandise such as indicated at A, the ends of the piece of wire 9 being overlapped as shown at 10 and 11 thus permitting the wire to be adjusted to fit merchandise articles of varying sizes. The length of wire 9 is crimped as shown at 12 to form an offset portion 13 that is engaged by the tongue 7, while the tongues 6 and 8 engage the length of wire at opposite sides of the crimped portion 12, also, as shown, the tongues 6 and 8 are folded oppositely to the tongue 7, and the folds engaging the wire 9 are arranged in staggered relation.

What is claimed is:—

1. A price tag holder, comprising a plate having means to hold a price card, tongues formed on the plate by incisions made therein, said tongues being folded on the plate, the folds of said tongues being in staggered relation, and a holding means adapted to engage an article of merchandise and secured to said plate under said folded tongues.

2. A price tag holder, comprising a plate of sheet metal having its edges folded thereon and spaced to provide a holder for a price card, a holding means secured to said plate consisting of a strand of wire adapted to engage an article of merchandise, said plate having tongues thereon formed by incisions made in the plate, and said tongues folded to engage said wire, said tongues being folded alternately in opposite directions and the folds of said tongues being in staggered relation.

3. A price tag holder, comprising a plate of sheet metal having its edges folded thereon and spaced to provide a holder for a price card, a holding means consisting of a strand of wire having an offset crimped portion, said plate having tongues thereon formed by incisions made in the plate, said tongues being folded on said plate to engage said wire, one of said tongues engaging said offset crimped portion, and other tongues engaging the wire at each side of said crimped portion.

In testimony whereof I affix my signature.

JOHN P. SIEBE.
